UNITED STATES PATENT OFFICE

2,463,154

SMALL ARMS EXPLOSIVE SHELL

Albert J. Coppotelli, Dixon, Ill.

Application December 20, 1944, Serial No. 568,978

1 Claim. (Cl. 102—56)

1

The present invention relates to new and useful improvements in explosive shells designed particularly for use as a shell for small arms and has for its primary object to provide the shell with an explosive charge.

An important object of the invention is to provide means for firing the charge upon impact of the shell with an object.

A further object of the invention is to provide an explosive shell of this character of simple and practical construction, which is efficient and reliable in use, relatively inexpensive to manufacture and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which the figure is a longitudinal sectional view of the explosive shell.

Referring now to the drawing in detail wherein for the purpose of illustration I have disclosed a preferred embodiment of the invention the numeral 5 designates a hollow shell or projectile of a type adapted for use as a cartridge, the shell being carried at the front end of a conventional form of cartridge (not shown) in the usual manner.

The front or nose end of the shell may be rounded as shown at 6, or may be tapered, if desired. The rear end of the shell is open and is provided with a plug 7 threaded therein and with which is formed a conventional tracer element 8 projecting rearwardly from the plug.

The front or nose end of the shell is filled with an explosive charge 9 which is compressed therein and held in place against the inner walls of the shell to maintain the charge 9 in a solid compact form, the charge extending to a point indicated at 10.

A cylindrical tube 11 has one end threaded to the inside of the plug 7 and in the rear end of which is slidably mounted a weighted disk or plunger 12 from which a stem 13 projects forwardly in the tube. In the front end of the stem 13 is threadedly attached a detonating cap 14 positioned forwardly of a cup-shaped guide 15 through which the pin 13 is slidably mounted.

2

A coil spring 16 is mounted on the pin 13 and is held under tension between the guide 15 and the plunger 12 to yieldably maintain the cap 14 in a rearward position in the guide 15 as shown in the drawing.

The guide 15 is formed with an outwardly projecting flange 17 at its edge for clamping between inner and outer retaining rings 18 and 19 threaded in the front end of the tube 11. The retaining rings 18 and 19 also serve to clamp the edges of a frangible cover 20 therebetween for enclosing the cap 14 within the guide 15 as a protector for the cap.

In the operation of the device, as the shell 5 is projected from the cartridge when fired from a rifle, machine gun or similar small arms weapon, the weighted plunger 12 and detonating cap 14 are held in their rearward position, as shown in the drawing, by the spring 16 as well as by the forward momentum of the shell 5, and when the nose 6 of the shell strikes an object the impact will cause the weighted plunger 12 to move forwardly against the tension of the spring 16 and force the cap 14 through the thin frangible closure 20 so as to strike the compressed rear end 10 of the charge 9, and fire the charge 9 causing an explosion of the shell.

As a safety measure the stem 13 may be provided with a shear pin 21 held against the rear of the guide 15 to prevent accidental forward movement of the detonating cap 14 should the spring 16 become crystallized or broken, the shear pin being broken by the force of the forward movement of the plunger 12 and stem 13 upon impact of the shell with an object.

It is believed that the details of construction, operation and advantages of the device will be readily understood from the foregoing without further detailed explanation.

Having thus described the invention, what I claim is:

An explosive shell, comprising a hollow body open at its rear end and having an explosive charge held in compact form in its front end, a plug threaded in the rear end of the body, a tube carried by the plug and projecting longitudinally in the body rearwardly of the charge, a weighted plunger slidably mounted in the tube and having a forwardly projecting stem, a detonating cap secured to the front end of the stem, a guide for

the stem and forming a chamber for the cap, a frangible cover for the chamber, means for securing the chamber and cover to the front end of the tube, means for releasably retaining the plunger rearwardly in the tube, said plunger being projected forwardly upon impact of the body with an object to cause contact of the cap with the charge to fire the latter, and a shear pin mounted on the stem transversely thereof, said shear pin being held normally against the guide to present accidental forward movement of the detonating cap, the said shear pin being breakable by the force of the forward movement of the plunger upon impact of the shell with an object.

ALBERT J. COPPOTELLI.
